[57] CLAIM

The ornamental design for a display stand, as shown and described.

DESCRIPTION

FIG. 1 is a perspective view of a display stand showing my new design;
FIG. 2 is a top plan view thereof;
FIG. 3 is a bottom plan view thereof;
FIG. 4 is a front elevational view thereof;
FIG. 5 is a right side elevational view of FIG. 4;
FIG. 6 is a sectional view taken along line 6—6 of FIG. 4;

FIG. 7 is a sectional view taken along line 7—7 of FIG. 4;

FIG. 8 is a top plan view of a second embodiment of a display stand in accordance with my new design;
FIG. 9 is a bottom plan view thereof;
FIG. 10 is a front elevational view thereof;
FIG. 11 is a right side elevational view of FIG. 10;
FIG. 12 is a sectional view taken along line 12—12 of FIG. 10;
FIG. 13 is a sectional view taken along line 13—13 of FIG. 10;
FIG. 14 is a top plan view of a third embodiment of a display stand in accordance with my new design;
FIG. 15 is a bottom plan view thereof;
FIG. 16 is a front elevational view thereof;
FIG. 17 is a right side elevational view of FIG. 16;
FIG. 18 is a sectional view taken along line 18—18 of FIG. 16;
FIG. 19 is a sectional view taken along line 19—19 of FIG. 16;
FIG. 20 is a top plan view of a fourth embodiment of a display stand in accordance with my new design;
FIG. 21 is a bottom plan view thereof;
FIG. 22 is a front elevational view thereof;
FIG. 23 is a right side elevational view of FIG. 22;
FIG. 24 is a sectional view taken along line 24—24 of FIG. 22;
FIG. 25 is a sectional view taken along line 25—25 of FIG. 22;
FIG. 26 is a top plan view of a fifth embodiment of a display stand in accordance with my new design;
FIG. 27 is a bottom plan view thereof;
FIG. 28 is a front elevational view thereof;
FIG. 29 is a right side elevational view of FIG. 28;
FIG. 30 is a sectional view taken along line 30—30 of FIG. 28;
FIG. 31 is a sectional view taken along line 31—31 of FIG. 28;
FIG. 32 is a top plan view of a sixth embodiment of a display stand in accordance with my new design;
FIG. 33 is a bottom plan view thereof;
FIG. 34 is a front elevational view thereof;
FIG. 35 is a right side elevational view of FIG. 34;
FIG. 36 is a sectional view taken along line 36—36 of FIG. 34; and
FIG. 37 is a sectional view taken along line 37—37 of FIG. 34.
